UNITED STATES PATENT OFFICE.

HARRY SUMMERFIELD STOUT, OF CEREDO, WEST VIRGINIA.

REINFORCED-CONCRETE POLE.

1,075,232.

Specification of Letters Patent.

Patented Oct. 7, 1913.

Application filed December 19, 1912. Serial No. 737,625.

To all whom it may concern:

Be it known that I, HARRY S. STOUT, a citizen of the United States, and a resident of Ceredo, in the county of Wayne and State of West Virginia, have invented a new and Improved Reinforced-Concrete Pole, of which the following is a full, clear, and exact description.

The invention relates to reinforced concrete poles, and has reference more particularly to the class comprising a metallic body covered with concrete.

An object of the invention is to provide an inexpensive reinforced concrete pole having a high co-efficiency of resistance to bending stresses, and sufficient resiliency to withstand shocks and to form a pole of uniform strength.

Reference is to be had to the accompanying drawings forming a part of this specification, in which similar characters of reference indicate corresponding parts in all the views.

Figure 1 is a vertical section through the concrete, of an embodiment of my invention, leaving the reinforcing parts in elevation; Fig. 2 is an elevation of the central reinforcing member; and Fig. 3 is a section on the line 3—3 of Fig. 1, with a tear in the lateral surface of the pole to show the way the horizontal reinforcing members are interconnected.

Before proceeding to a more detailed description of my invention, it must be understood that the cross section of the pole may be circular or polygonal. The central tubular reinforcing member may be filled also with concrete, and the exterior appearance of the pole may be varied in accordance with individual preference or special conditions, without departing from the underlying spirit of the invention.

In the appended drawings, 10 is the vertical tubular central member, preferably circular in cross section, and on its exterior lateral surface provided with a plurality of longitudinal ribs 11 parallel to the elements forming the lateral surface, the ribs being equally distributed on the surface, and their number preferably corresponding to the number of sides the pole is to have. A series of rings 12, preferably formed from a round

iron rod, are placed horizontally and concentric with the tube 10. These rings 12 are consecutively increasing in diameter 55 from the upper end to the lower end, and their consecutive vertical distance is gradually diminished from the top to the bottom of the pole. The gradual increase in the diameter of the rings and the gradual decrease of the distance between them are for the purpose of giving the lateral surface of the pole the desired slope and to form a pole of uniform strength.

The rings 12 are maintained concentric 65 with the tube 10 by means of wire members 13 engaging the orifice 14 in the rib 11 and having on each side of the rib wire portions 15 wound about the rings 12, and then continued to the lower ring 12 and again wound 70 about the same, with the end portions 16 of the wire members 13. The purpose of this interconnection between two consecutive rings by means of wire is to keep them apart at a desired distance from each other. The 75 wire member 13 not only keeps the horizontal rings 12 in a predetermined position, but also reinforces the structure. The horizontal ring 12 is placed below the lower end of the central tubular member 10 for the purpose of giving to the base a greater surface strength. Near the upper end of the central tubular member 10 a bolt 17 projects through the lateral surface of the same, the shorter 80 projecting end of the pole having an anchor 85 plate 18, and the other end being provided with threads and a nut 19 adapted to support a member 20 for insulator brackets. The so-formed skeleton of the central tubular member 10, horizontal rings 12 and wire 90 members 13, is covered with concrete 21, and the shape of a hexagon is preferably given to the so-formed pole, the bolt 17 being anchored in the concrete by means of the plate 18. The edges of the polygon forming the 95 pole are made to lie on the same radial line with the rings provided on the tube 10 so as to add strength to the edges, particularly at the upper part of the pole, where it is most needed.

A pole constructed according to the above description will not only be of uniform strength throughout, but, due to its vertical tubular member, its bending moment will

be greatly increased, and the concrete housing will add still more to it. The horizontal rings with wire bindings in the concrete housing, will greatly increase the resistance to flexural stresses of the pole and add surface to the support of the concrete.

As in all cases of reinforced concrete structures, the skeleton part must be very well distributed in the concrete body so as to form a structure of uniform resistance, and, as will be seen from the drawings, my pole has the skeleton uniformly covered with concrete, the reinforcing parts being well distributed in the body of concrete.

Having thus described my invention, I claim as new and desire to secure by Letters Patent:

1. In a reinforced concrete pole, a skeleton comprising a central member having exterior lateral ribs, a plurality of rings varying in size concentric with said central member, and a plurality of binding means from each of said rings to said ribs and a plurality of binding means from each of said rings to the following ring, said binding means and said rings forming substantially a cone-shaped cage about said central member, and a series of superposed cone-shaped cages within said first-mentioned cone-shaped cage.

2. In a reinforced concrete pole, a skeleton comprising a central member having exterior lateral ribs, a plurality of rings, each consecutive ring changing in diameter and all concentric with said member, and a plurality of binding means from each of said rings to said ribs and a plurality of binding means from each of said rings to the following ring, said binding means and said rings forming substantially a cone-shaped cage about said central member, and a series of superposed cone cages within said first-mentioned cone cage.

3. In a reinforced concrete pole, a skeleton comprising a central vertical tubular member, having ribs on its exterior lateral surface, a plurality of rings each consecutive changing ring in diameter, concentric with said central member and normal to it, the distance between said consecutive rings being gradually changed, and means associated with said ribs on said central member and said rings to maintain said rings normally concentric to said central member and at a predetermined distance.

4. In a reinforced concrete pole, a skeleton comprising a central vertical tubular member having reinforcing ribs on its exterior surface, and near its upper end means adapted to support an object, a plurality of rings each consecutive ring changing in diameter, concentric with said central vertical tubular member and normal to it, the distance between said consecutive rings being gradually changed, and means associated

with said ribs and said consecutive rings to maintain said rings normal and concentric to said central vertical tubular member and at a predetermined distance.

5. In combination a skeleton comprising a central exteriorly laterally ribbed tubular member, a plurality of horizontal rings each consecutive ring changing in diameter and all concentric with said central tubular member, said rings consecutively changing in distance between each other, and the change in distance between any two consecutive rings being inversely to their diameters, means for connecting said rings to said central tubular member, and for maintaining said rings concentric with said central tubular member and at a predetermined distance, and a concrete body incorporating said skeleton uniformly and centrally and having sides corresponding in number with the ribs on said central tubular member, and means provided near the upper part of said tubular member and projecting out of said concrete body adapted to support an object.

6. In combination, a skeleton comprising a central exteriorly laterally ribbed tubular member, a plurality of horizontal rings each consecutive ring changing in diameter and all concentric with said central tubular member, said rings consecutively changing in distance between each other, and the change in distance between any two consecutive rings being inversely to their diameters, means for connecting said rings to said central tubular member, and for maintaining said rings concentric with said central tubular member and at a predetermined distance, and a concrete body incorporating said skeleton uniformly and centrally so as to form a pole of uniform strength, said pole having its number of sides equal to the number of ribs on said central tubular member, said ribs and edges forming the sides of said concrete body lying on the same radial line, and a bolt near the upper end of said central tubular member projecting through the lateral surface of same and having at one end a plate anchored in said concrete body and the other end projecting through said concrete body and adapted to carry an object.

7. In a reinforced concrete pole, a skeleton comprising a central member having exterior lateral ribs, a plurality of rings each consecutive ring changing in diameter and all concentric with said member, and a plurality of binding means from each of said rings to said ribs, said means with said rings forming a series of superposed cones about said central member.

8. In a reinforced concrete pole, a skeleton comprising a central member having exterior lateral ribs, a plurality of rings concentric with said member, and a plurality of binding means from each of said rings to

said ribs, forming a series of superposed cones about said central member, said superposed cones having their bases gradually increasing in diameter from the upper part 5 of said central member to the lower part of the same.

In testimony whereof, I have signed my

name to this specification in the presence of two subscribing witnesses.

HARRY SUMMERFIELD STOUT.
